UNITED STATES PATENT OFFICE

2,197,297

STOVE

Sanford Forrest Caudill, Shelbyville, Ky.

Application August 11, 1939, Serial No. 289,685

1 Claim. (Cl. 126—59.5)

My invention relates to improvements in stoves and the particular object in view is to provide an inexpensive, practical and portable stove adapted for burning coke and for use in heating tobacco barns and the like in curing tobacco.

To the accomplishment of the above, and subordinate objects presently appearing, a preferred embodiment of my invention has been illustrated in the accompanying drawings, set forth in detail 10 in the succeeding description, and defined in the claim appended hereto.

In said drawings:

Figure 1 is a view in front elevation of the preferred embodiment of my invention,

15 Figure 2 is a view in side elevation,

Figure 3 is a view in transverse section taken on the line 3—3 of Figure 1 looking downwardly and drawn to an enlarged scale,

20 Figure 4 is a view in vertical section taken on the line 4—4 of Figure 1 looking in the direction indicated by the arrows and drawn to an enlarged scale.

Figure 5 is a fragmentary view in top plan of the casing of the stove.

25 Referring to the drawings by numerals, in the illustrated embodiment thereof, my improved stove comprises a cylindrical casing 1, of suitable metal, preferably steel, designed to rest on any selected support, such as a floor, in up-ended position and having an open bottom end 2 provided with a front square cut-out 3 extending upwardly from the bottom edge of the casing for a short distance to provide a lower doorway in said casing. A pair of vertical guides 4 are provided at opposite sides of the cut-out 3, or doorway, respectively. A suitable door 5 of sheet metal is slidably mounted at opposite edges thereof in said guides 4, with a friction fit in said guides, whereby the door may be adjusted to different set positions in said guides. The door 5 is provided with a forwardly extending handgrip 5' for use in raising and lowering the same.

30 Immediately above the cut-out, or doorway, 3 a disk-like metal grate 6 is provided in the casing 1, said grate having formed therein draft apertures 7. The grate 6 is rotatably supported in the casing 1 by means of brackets 8 suitably secured to the inner wall of the casing and upon which said gate loosely rests. A radial edge lug 9 on said grate 6 extending through a circumferential slot 10 provided in the casing 1 forms a handgrip by means of which the grate may be oscillated to shake the same.

35 A particular feature of my invention is a combination closure and heat spreader plate 11, pref-

erably of circular form and larger diameter than that of the casing, surmounting the open top of the casing 1 horizontally and mounted on the latter for vertical adjustment toward and from said top and also for swinging movement edge-wise to clear the top all for a purpose presently seen. The plate 11 may be formed of any suitable material such as sheet metal.

40 The mounting for the plate 11 comprises a slide rod 12 depending from the under side of said plate and suitably secured at its upper end thereto, and a pair of vertically spaced eye-like lugs 13 provided on the rear side of the casing 1 adjacent the top thereof in laterally extending position and in which said rod 12 may be extended for vertical sliding and rotary adjustment therein. The rod 12 and lugs 13 may be secured to the plate 11 and casing 1 in any desired manner. A hand grip such as shown at 14 is provided on top of the plate 11 for manipulating the same. As best shown in Figures 1 and 4 the rod 12 is secured to said plate 11 in eccentric relation to the axis of the plate such that the latter may be swung about the axis of the rod into concentric or eccentric relation to the top of the casing 1.

45 In operating the stove, as so far described, the plate 11 is adjusted vertically to the desired height above the top of the casing 1 to vary the draft and function as a spreader deflecting the heat laterally from said top. By swinging the 50 plate 11 it can be moved from a position over the stove to a position to one side thereof, as shown in dotted lines in Figure 2, so that fuel can be placed in the stove and when the fuel has been placed in the stove the plate is turned back to its original position to diffuse and spread the heat. By lowering or raising the plate it acts as a damper or draft control. As will be understood, since the slide rod 12 is disposed eccentrically of the plate 11, the latter in any position thereof over-balances the rod 12 in the lugs 13 causing said rod to bind in said lugs so that the plate is thereby held in any adjusted position. When it is desired to load the stove, the plate 11 may be 55 swung to clear the top of the casing 1 for convenient access thereto.

55 The elements 20 are handgrips on the casing 1 for lifting the same and need merely be mentioned in passing. The door 5 is used for regulating the draft.

50 The foregoing will, it is believed, suffice to impart a clear understanding of my invention without further explanation.

55 Manifestly the invention, as described, is susceptible of modification and right is herein re-

served to such other modifications as fall within the scope of the subjoined claim.

What I claim is:

- A stove of the class described comprising an upstanding casing having an open top end, a combined closure and heat spreader plate of larger area than the cross-sectional area of said end of the casing, and means to mount said plate on said casing for vertical adjustment above said
- 5 end and edgewise swinging movement into and
- 10

from surmounting relation thereto comprising a slide rod depending from said plate eccentrically thereof, and a pair of apertured guide lugs extending laterally from said casing in vertically spaced relation, said rod being slideable and rotatable in said lugs, said plate over-balancing said rod in said lugs to cause the rod to bind in the lugs and thereby frictionally hold the plate in adjusted position.

SANFORD FORREST CAUDILL. 10
